UNITED STATES PATENT OFFICE.

LOUISE E. RINGELSTEIN, OF NEW YORK, N. Y.

SAFETY CLOTHESLINE ATTACHMENT FOR WINDOWS.

1,334,795.

Specification of Letters Patent. Patented Mar. 23, 1920.

Application filed April 5, 1919. Serial No. 287,685.

To all whom it may concern:

Be it known that I, LOUISE E. RINGELSTEIN, a citizen of the United States, and residing at New York, in the county of Bronx 5 and State of New York, have invented certain new and useful Improvements in Safety Clothesline Attachments for Windows, of which the following is a specification, such as will enable those skilled in the art to 10 which it appertains to make and use the same.

The object of this invention is to provide a clothesline attachment for the windows of apartments in flats or other dwellings in connection with which an endless clothesline is 15 employed, and the construction and operation of which is such that clothes or other articles may be placed on the line to dry and removed therefrom when dried by an 20 operator standing within the room or apartment and without danger of accidents or injury which frequently accompany operations of the class referred to; and with this and other objects in view the invention consists 25 in a device or apparatus of the class specified, constructed and operated as hereinafter described and claimed.

The invention is fully disclosed in the following specification, of which the accompanying drawing forms a part, in which the separate parts of my improvement are designated by suitable reference characters in each of the views, and in which:—

Figure 1 is a sectional view showing one 35 side of a window frame and the top and bottom or outer and inner sashes mounted therein and showing my invention in position for use;

Fig. 2 a partial section on the line 2—2 of Fig. 1 and showing a part of the invention when not in use;

Fig. 3 a partial section on the line 3—3 of Fig. 2;

Fig. 4 a sectional view on the line 4—4 of Fig. 1, and,

Fig. 5 a section on the line 5—5 of Fig. 1.

In the accompanying drawing I have shown at *a* one side of a window frame and at *b* and *c* a top or outer and a bottom or inner sash respectively, and, in the practice of my invention, I provide a bracket *d* which is secured to the outside of a window frame at a predetermined point, preferably just below the bottom of the top or outer sash *b* 55 when the latter is in a closed position, and

into which is screwed a bolt *d*² provided with a head *d*³.

I also provide an arm *e* one end of which is provided in the form of construction shown with a head *e*², which is screwed thereonto and into which is screwed a rod *e*³ on which is mounted a sleeve *e*⁴, which is held in place by a threaded nut *e*⁵, and between the inner end of the sleeve *e*⁴ and the head *e*² is rotatably mounted a main pulley *f*¹ having a shank *f*² through which the rod *e*³ passes, and the sleeve *e*⁴ is provided centrally of one side thereof with a stud *e*⁶, and a screw pin *g* having a head *g*² is passed through the head *d*³ of the bolt *d*² to rotatably connect the sleeve *e*⁴ with the head of said bolt.

The pulley *f*¹ comprises a body portion through which is passed a pin *f*³ on which the usual grooved wheel *f*⁴ is mounted, and rotatably mounted on one end of the pin *f*³ is a supplemental pulley *h*, said supplemental pulley *h* comprises a U-shaped frame *h*² in which is mounted the usual grooved wheel *h*³, and while one side of the U-shaped frame *h*² is rotatably mounted in connection with the pulley *f*¹, the other side of said frame is bent outwardly laterally to form a hook-shaped member *h*⁴.

Connected with the free end of the arm *e* 85 is a spiral or open hook member *i*, this connection being made in any desired manner, and detachably and loosely connected with said spiral or open hook member is a pulley *i*² with which the clothesline *j* is adapted to 90 be connected as shown and as hereinafter described.

Secured to the outside of the window frame and at a predetermined distance below the bracket attachment *d* is a bracket 95 arm *k* provided at its end with an open spring clamp *k*² adapted to receive the arm *e* when the latter is in a vertical position, and secured to the inner side of the window frame and approximately in a transverse line 100 with the bracket attachment *d*, in the form of construction shown, is a keeper *m* in which is rotatably mounted an arm *m*² provided at its end with a clamp *m*³ which opens upwardly and which is adapted to support 105 the arm *e* in a horizontal position as shown in full lines in Fig. 1.

With this construction the arm *e* may be swung in a vertical plane into the horizontal position shown in Fig. 1, in which posi- 110

tion said arm will project inwardly of the window or window frame and into the room or compartment a considerable distance, or said arm may be lowered into the vertical position shown in dotted lines in Fig. 1, in which it may be engaged with the bracket arm *k*, or clamp device *k*² with which said arm is provided, and the arm *e* may also be swung in various other planes at different 10 angles to the side of the window frame with which said arm is connected.

It will be understood that the line *j* is, in use, passed around a pulley supported at a proper or predetermined distance from the 15 window or window frame, and the upper part *j*² of said line is passed through the pulley *f*, around the pulley *i*² and the lower part *j*³ of said line may be connected with or passed through the pulley *h* when desired, 20 or disengaged from said pulley as will be readily understood.

When this device is not in use the part *j*³ of the line is connected with the pulley *h* as indicated in dotted lines in Fig. 3, and 25 the arm *e* is supported in a vertical position outside of the window sashes as is also indicated in dotted lines in Fig. 1, and when it is desired to place articles to be dried on said line, the lower sash is raised, the upper sash 30 being presumed to be in its raised position, and the arm *e* is detached from the bracket arm *k* and is raised into the full line position shown in Fig. 1, in which position said arm extends inwardly of the window frame 35 and a predetermined distance into the room or compartment. The part *j*³ of the line is then detached from the pulley *h* and an operator standing in the room or compartment may hang articles to be dried on the 40 part *j*³ of the line in which operation the line is moved around its supports in the direction of the arrows *x* by grasping the bottom part *j*³ thereof, and this operation is repeated or continued until all the articles to 45 be dried are placed upon the line, after which the part *j*³ of the line is engaged with the pulley *h* and the arm *e* swung downwardly into the position shown in dotted lines in Fig. 1, after which the inner or bottom sash of the window may be closed; and 50 when the articles on the line are dried and it is desired to remove them from the line the inner or bottom sash is raised, the arm *e* also raised into the position shown in full 55 lines in Fig. 1, and the line *j* is manipulated by means of the bottom part *j*³ thereof to move said line in the direction of the arrows *x*², in which operation the said articles are removed from the line in the usual manner.

60 With my improvement the danger of falling out of the window which frequently happens in operations of the class herein referred to, is totally obviated and any danger of such accidents avoided, and the op-

eration of placing articles to be dried on the line and removing them therefrom is rendered a simple one which may be easily performed by the operator without stress or strain, or the danger usually accompanying operations of this class.

70 Although I have shown and described the preferred means for carrying my invention into effect, such invention is not limited to the details of construction herein shown and described, and changes therein and modifications thereof may be made, within the scope of the appended claims, without departing from the spirit of the invention or sacrificing its advantages.

Having fully described my invention, what 80 I claim as new and desire to secure by Letters Patent, is:—

1. In an apparatus of the class described, a bracket attachment adapted to be secured to the outside of a window frame, a rotatable 85 arm holder mounted in connection with said bracket attachment and adapted to swing horizontally and vertically, an arm rotatably mounted in connection with said holder, a main pulley rotatably mounted on 90 said arm adjacent to said holder, a supplemental pulley rotatably mounted in connection with the main pulley and suspended therefrom and provided with an open side, and another pulley loosely and detachably 95 connected with the free end of said arm.

2. In an apparatus of the class described, a bracket attachment adapted to be secured to the outside of a window frame and provided with a rotatable arm holder, a main 100 arm loosely and rotatably mounted in connection with said holder and adapted to swing vertically and horizontally and in different planes at different angles to the window frame, a bracket arm adapted to be secured to the window frame below the bracket attachment and provided with a spring clamp adapted to hold said arm in a vertical position and a supplemental arm rotatably mounted in connection with the inner 105 side of the window frame and adapted to hold the main arm in a horizontal position, said main arm being also provided adjacent to said bracket attachment with a pulley 110 rotatable transversely thereof and having 115 a supplemental pulley loosely suspended therefrom and provided with an open side, said main arm being also provided at its free end with a pulley which is loosely and detachably connected therewith.

120 In testimony that I claim the foregoing as my invention I have signed my name, in presence of the subscribing witnesses, this 3rd day of April, 1919.

LOUISE E. RINGELSTEIN.
